[57] CLAIM

The ornamental design for a spatula attachment for electric knife drive unit, as shown and described.

DESCRIPTION

FIG. 1 is a perspective view of a spatula attachment for electric knife drive unit showing my new design;

FIG. 2 is a left side elevational view thereof;

FIG. 3 is a top plan view thereof;

FIG. 4 is a perspective view of a second embodiment of that shown in FIG. 1;

FIG. 5 is a left side elevational view of FIG. 4; and

FIG. 6 is a bottom plan view of FIG. 4.

The handles in FIGS. 1 and 4 are shown in broken line for illustrative purpose only.

FIG. 1

FIG. 2

FIG. 3

FIG. 4

FIG. 5

FIG. 6
